UNITED STATES PATENT OFFICE.

JOHN J. HIGGINS, OF NEW YORK, N. Y., ASSIGNOR TO E. & H. T. ANTHONY & CO., OF SAME PLACE.

PHOTO-CHRONOGRAPH.

SPECIFICATION forming part of Letters Patent No. 351,108, dated October 19, 1886.

Application filed February 12, 1886. Serial No. 191,757. (No model.)

To all whom it may concern:

Be it known that I, JOHN J. HIGGINS, of the city, county, and State of New York, have invented a new and useful Improvement in Photo-Chronographs, of which the following is a specification, reference being had to the annexed drawings, forming a part thereof, in which—

Figure 1 is a front elevation. Fig. 2 is a front elevation with the dial and casing removed. Fig. 3 is a vertical transverse section taken on line $x-x$ in Fig. 1. Fig. 4 is a detail view of the photographic record of the photo-chronograph. Figs. 5 and 6 are detail perspective views.

Similar letters of reference indicate corresponding parts in the different figures of the drawings.

In the practice of photography no convenient and reliable method for determining the period of exposure of sensitive plates through the drop-shutter has been available.

The object of my invention is to provide a simple, inexpensive, and efficient chronograph for determining the period of exposure of any drop-shutter or for making a permanent record from which the duration of the exposure may be determined.

My invention consists in a graduated dial and an arm revolving in front of the dial and carrying a light-reflecting surface, and, in combination with the motor employed in driving the arm, of a slow-moving calibrating-wheel whose period of rotation bears a fixed relation to that of the arm, and an audible signal operated once during each rotation of the slow-moving wheel to facilitate calibration.

The motor A, which drives the arm and the slow-moving wheel, in the present case is a spring-motor formed of the wheels B C D, secured to arbors a b c , the arbor a being connected with the driving spring, the first wheel, B, meshing into the pinion d on the arbor b , the wheel C meshing into the pinion e on the arbor c . The wheel D on the arbor c meshes into a pinion, f , on the arbor g , and the arbor g carries a fan, h , for controlling the movement of the spring-motor.

Upon an arbor, i , journaled in the motor-frame, is secured a pinion, j , which is driven

by the wheel B. The arbor i also carries a brake-wheel, k , which is pressed by a brake-spring, l , secured to a stud, m , journaled in a support attached to the back of the chronograph-casing, as clearly shown in Fig. 5. 55 Upon the stud m , outside of the casing, is secured an arm, n , provided with series of holes o for receiving a pin entering holes in the casing, for retaining the arm n in any desired position, thus holding the brake-spring l under 60 more or less tension.

Upon an arbor, p , journaled in the motor-frame and projecting through the dial E upon the front of the chronograph-casing, is secured a pinion, q , which is engaged by the 65 spur-wheel D. To a bracket, r , secured to the back of the chronograph-casing is pivoted a lever, s , having at one end a right-angled arm, t , which reaches into the movement in position to touch the arbor p when the lever is moved 70 in the manner presently to be described, as shown in Fig. 6. To the opposite and shorter end of the lever is secured a plate, u , and a rod, v , extends through the front of the casing in position to be touched by the bezel w 75 when it is closed down over the dial E, so that when the bezel w is closed the rod v will push against the plate u on the end of the lever s and bring its right-angled end t into frictional contact with the arbor p , thus arresting the 80 movement of the motor, and when the bezel w is opened, the rod v being relieved of pressure, the angled end t of the lever s will be carried away from the arbor p by a spring, a' , secured to the back of the chronograph-casing and 85 pressing against the back of the shorter arm of the lever.

On a support, b' , secured to the back of the casing, is pivoted a bell-hammer, c' , in position to strike the bell d' , and to the arm of 90 the bell hammer is secured a wire, e' , which extends into the motor in position to be engaged by the pin f' , carried by the brake-wheel k , once during each revolution of the brake-wheel.

The dial E, which is placed in the front of the casing and covers all the moving parts of the apparatus excepting the arm F, has a circular opening, g' , opposite and concentric with the arbor i , and to the arbor i is secured a 95

wheel, h' , carrying a diametrical line, i' , which serves as an index and coincides twice during each revolution with marks j' on the dial at the sides of the opening g' . The dial is provided with four principal graduations formed by the lines k' , which cross each other at right angles, intersecting at the arbor p , and the larger graduations are subdivided by short radial lines l' , extending from the periphery of the dial a short distance toward the center thereof,

The arm F is carried by a boss, m' , received on the arbor p , and consists of a straight bar of metal having parallel edges. Upon one end of the arm F is placed a plate, G, provided with spring-clips n' , projecting from the back thereof, at right angles, and embracing the sides of the arm F.

The dial E is preferably made black, and the graduations thereon are formed of white lines, and the outer surface of the plate G is also white.

Any motor which will impart a continuous uniform rotary motion to the bar F will answer the purposes of my invention. Therefore I do not limit or confine myself to the exact form of motor herein shown and described.

The method of using my improved chronograph is as follows: The bezel w is opened, releasing the movement in the manner described, allowing the wheel h' and the arm F to revolve. In the present case the gearing of the motor is so proportioned that the arm F makes five hundred and twenty revolutions while the wheel h' makes one revolution, and the user of the chronograph determines the time required to complete five hundred and twenty revolutions of the arm F by timing the interval between two successive strokes of the bell by means of any convenient time-piece.

The operator then knows the rate of rotation of the arm F, so that when the plate G, carried by the arm F, is photographed during its rotation the image produced upon the sensitive photographic plate may be utilized to determine the duration of the exposure of the plate. If, for example, the arm F makes five hundred and twenty revolutions in one minute, it will make 8.66 revolutions in one second; and if the image produced on the plate covers one-fifth of the circle over which the plate G, carried by the arm, travels it indicates that the image has been produced in 0.22 of a second, as the time required for one revolution of the arm F is approximately .11 of a second.

In the part of a photograph of a dial and the moving plate G, (shown in Fig. 4,) I represents the curved light streak produced on the sensitive plate by light reflected from the plate G while the chronograph is in motion. It will thus be seen that the light streak produced on the photographic plate indicates the time of the exposure, and consequently affords a legible and permanent record of the action of the drop-shutter.

I have shown in connection with the motor a fan, h , for retarding and regulating its motion; but by proportioning the width of the

bar F to the strength of the spring of the motor the fan h may be dispensed with, as the bar F will then act as a regulator to the movement of the motor.

Owing to the facility with which my improved chronograph can be calibrated, no extreme accuracy is required in its construction, so that, if desirable, it may be tested at each operation.

When it becomes necessary to reduce the velocity of the plate G for slow-working sensitive plates, the plate can be slid along the bar F toward the arbor p , thus causing it to revolve in a smaller circle; or the speed of the movement may be varied by applying more or less pressure to the brake-wheel k by means of the spring l .

By employing an audible signal in connection with the calibrating device greater accuracy is secured than will be possible by merely observing the calibrating-wheel.

Having thus fully described my invention, what I claim as new, and desire to secure by Letters Patent, is—

1. In a photo-chronograph, a light-reflecting plate and means for carrying it in a circular path, substantially as herein shown and described.

2. The combination, in a photo-chronograph, of the rotating arm F and the light-reflecting plate G, adjustably secured to the arm, substantially as herein shown and described.

3. In a photo-chronograph, the combination, with the rotating arm F and light-reflecting plate G carried thereby, of the calibrating-wheel h' , having a rotary motion bearing a fixed relation to the motion of the arm F, substantially as herein shown and described.

4. In a photo-chronograph, the combination, with the rotating arm F, having a light-reflecting surface, of the calibrating-wheel h' , having a rotary motion bearing a fixed relation to the motion of the arm F, substantially as described.

5. In a photo-chronograph, the combination, with the revolving arm F, light-reflecting-plate G carried thereby, of the calibrating-wheel h' , and a sound mechanism operated substantially as herein shown and described.

6. The combination, with the rotating arm F and light-reflecting plate G carried thereby, of the graduated dial E, having a dark ground and light graduated lines formed thereon, substantially as herein shown and described.

7. In a photo-chronograph, the combination, with the arm F and light-reflecting plate G carried thereby, of a motor for imparting continuous rotary motion to the arm, substantially as herein shown and described.

8. In a photo-chronograph, the combination, with the rotating arm F, light-reflecting plate G, and mechanism for rotating the arm F, of a brake mechanism for regulating the velocity of the motor, substantially as herein shown and described.

9. The combination, with the light-reflect-

ing plate G, arm F, and arbor p, carrying the same, of the lever s, having the angled end t, and the rod v, adapted to be pressed by the bezel when closed over the dial, substantially as and for the purpose specified.

10. In a photo-chronograph, the combination, with the motor provided with the wheels B C D, of arbors a b c p i, the pinions b, g, and j, carried by the arbors, the brake-wheel k, secured to the arbor i, the adjustable brake-spring l, the pin f', projecting from the side of the brake-wheel, the bell-hammer c', the bell d', the calibrating wheel h', the arm F, and light-reflecting plate G, carried thereby, substantially as herein shown and described.

11. The method of recording the time of ex-

posure of a sensitive photographic plate, consisting in exposing a sensitive photographic plate to a light-reflecting plate revolving in front of a graduated dial at a known rate of 20 revolution, developing the plate, and finally calculating the time of exposure by comparing the length of the image of the light-reflecting plate with the length of the path of the light-reflecting plate and the period of its revolution, substantially as herein shown and described. 25
